UNITED STATES PATENT OFFICE.

EUGENE F. CAIRE, OF ST. PATRICKS, LOUISIANA.

RAILWAY-RAIL JOINT.

1,224,851.

Specification of Letters Patent.

Patented May 1, 1917.

Application filed July 10, 1916. Serial No. 103,427.

To all whom it may concern:

Be it known that I, EUGENE F. CAIRE, a citizen of the United States, residing at St. Patricks, in the parish of St. James and State of Louisiana, have invented new and useful Improvements in Railway - Rail Joints, of which the following is a specification.

This invention relates to a railway rail joint, and one of the principal objects of the invention is to so construct the meeting ends of two rails as to permit of an interengagement between the same whereby the rails may be connected without the employment of fish plates, bolts or analogous devices.

With the above and other objects in view the improvement resides in the construction, combination and arrangement of parts set forth in the following specification and falling within the scope of the appended claim.

In the drawings:

Figure 1 is a top plan view of two rails connected in accordance with the present invention,

Fig. 2 is a central longitudinal sectional view approximately on the line 2-2 of Fig. 1,

Fig. 3 is a longitudinal sectional view approximately on the line 3-3 of Fig. 1,

Fig. 4 is a transverse sectional view approximately on the line 4-4 of Fig. 1,

Fig. 5 is a perspective view of one of the rail ends, and

Fig. 6 is a similar view of the co-acting rail end.

Before entering into a detail description of my improvement, I desire to state that I am acquainted with the fact that rail joints have been produced wherein one of the rails is provided with a central extension which may terminate in an enlargement or head and that the other rail is provided with a groove or recess to receive the said extension and head and while my improvement necessarily embodies these features the arrangement of the same is such that a wedging effect is provided between the walls of the slot in one of the rails and the extension of the other rail which is disposed in the said slot whereby when the rails are assembled danger of a vertical movement of the same will be prevented and also whereby the wedging effect of the interengaging elements is such as to positively prevent one of the rails sinking below the other rail and as a

consequence the rails will be at all times maintained in proper alignment.

As shown in the accompanying drawings, the rails are of the ordinary construction but each of the rails, indicated for distinction by the numerals 1 and 2 respectively have their webs thickened at their ends.

The thickened end of the rail 1 is provided with an extension 3, the opposite walls of said extension being inclined toward the end thereof and terminating in a rounded head 4. The sides of the extension converge to the lower edge thereof and the head is conical from its top to its bottom end. Thus the head is of a substantial frusto-conical form and the lower wall of the said head, indicated by the numeral 5, is parallel with the upper wall thereof or in other words is horizontally straight while the extension 3 from its juncture with its head to that of its connection with the rail end is beveled or inclined downwardly, as indicated by the character 6.

The thickened end of the rail 2 is provided with a longitudinally extending groove 7 which has its walls beveled or inclined inwardly from the head of said rail toward the base of the rail. The groove terminates in a rounded recess 8 and this recess is shaped to snugly receive the frusto-conical head of the extension of the rail 1. The lower wall provided by the recess 8 is horizontally straight, while the lower wall of the groove 7 inclines from the said lower wall of the depression outwardly toward the base of the rail so that the inclined lower edge 6 of the extension 3 will snugly engage with the referred to lower wall provided by the groove 7 and likewise whereby the lower wall 5 of the head 4 of the said rail 1 will be firmly seated upon the horizontally straight lower wall of the depression 8. It is, of course, to be understood that the connecting elements of the rails are spaced to provide for a limited longitudinal movement of the rails incident to the expansion and contraction thereof, but from the above description, taken in connection with the drawings, it will be noted that no securing elements, such as bolts and nuts, fish plates, rail chairs or analogous elements are required for connecting the ends of the rails.

Having thus described the invention, what I claim is:

A rail joint comprising two rails each

having their webs, at their ends, thickened, one of the rails having its end formed with an extension which terminates in a rounded head, the side walls of the extension converging from their upper edges to their lower edges and likewise the head of said extension being beveled to provide a substantially frusto-conical member, the lower wall of the head being parallel with the upper wall thereof, the lower wall of the extension inclined downwardly at its juncture with the head to its connection with the end of the rail, and the other rail having a longitudinal

groove which terminates in a rounded recess and the walls provided by the groove and recess being shaped to correspond with the outer surfaces of the extension of the head thereof whereby the said extension when received in the groove and recess will be wedged against the walls of the said recess and also whereby the tread surfaces of both of the rails will be thus maintained in alignment.

In testimony whereof I affix my signature.

EUGENE F. CAIRE.
